UNITED STATES PATENT OFFICE.

LEWIS G. KELLOGG, OF CHICAGO, ILLINOIS.

WARDROBE-BED.

SPECIFICATION forming part of Letters Patent No. 360,022, dated March 29, 1887.

Application filed May 22, 1886. Serial No. 202,964. (No model.)

To all whom it may concern:

Be it known that I, LEWIS G. KELLOGG, a citizen of the United States, residing at Chicago, Illinois, have invented certain new and useful Improvements in Wardrobe-Beds, of which the following is a specification.

In the drawings, Figure 1 is an end elevation of my improved wardrobe-bed. Fig. 2 is a rear elevation of the same. Fig. 3 is a vertical section taken through Fig. 1, showing the bed-body down. Fig. 4 is a side elevation showing the bed-body down, with a base-extension thrown out to prevent tipping or pulling over the standing portion of the bed-frame; and Fig. 5 is a detail view showing the method of connecting the vertical sliding back pieces and springs with the movable head-board.

In the drawings, A represents the permanent or standing portion of the bed; B, the folding portion of bed-body; C, the movable head-board; D, a bar carrying the standards to which the spring-connections are attached; E, such standards; F, ropes or connections connecting the standards with the springs; G, such springs; H, segments around which the springs bend; I, pulleys; J, the base-extension; K, a rod connecting the bed-body with the base-extension; L, anti-friction rollers fitting in circular bearings on the bed-body.

In making my improved wardrobe-bedstead I make a permanent or upright portion, which is intended to remain standing at all times. This portion is provided with a base of sufficient width to make its position on the floor

permanent and stable. To increase its capacity to resist any tendency to tip or pull over in lowering the bed-body or folding portion of the bed, I provide an extension to the base, which is thrown forward by the act of lowering the bed-body. This base-extension may be made by cutting a piece in the form of a segment or quarter-circle in the sides of the permanent or standing portion of the bed, so that it will fit into its place when the bed is up, as shown in Fig. 1, and open out and extend the base or width of the standing portion of the bed the length of its height, as shown in Fig. 4. This portion J may as readily be made of a separate piece from the side of the standing portion and placed just

inside of the same. In either case it is pivoted to such standing portion at its lower front corner. A bar, K, is pivoted to the lower rear corner at one end, and toward the other end it is pivoted to the main standing portion of 55 the bed-frame as a fulcrum. Beyond this fulcrum it extends a certain distance and terminates in an eye, which is pivoted to another bar or link, M, which link in turn is pivoted at its upper end to the folding portion of the 60 bed. When the bed-body is lowered, this link M, moving with the same, bears upon the upper end of the bar K, and causes it to turn on its pivot or fulcrum, lowering or depressing the end to which such link is connected. This of 65 course causes the lower end of the bar K to rise, and to lift with it the lower rear corner of the piece J, which turns on its pivot with the permanent portion of the bed. When the bed-body is lowered, the bar K and link M are in 7c the position shown in Fig. 3, at which time the base-extension J will rest upon the floor, and thus in effect increase the width of the permanent portion of the bed the distance of 75 its height. In this way much greater strength and stability are imparted to the permanent portion of the bed, and all tendency to tip or pull over the same effectually prevented. Any other equivalent method of connecting the bar K with the folding portion of the bed may be 80 employed, as the only object of such connection is to permit the folding portion of the bed to operate upon the bar K and throw out the base-extension J.

To connect the bed-body or folding portion 85 of the bed with the permanent or standing portion, I make ways or bearings in each of the side rails of the bed-body at a proper distance from the lower end when the bed-body is folded up to permit the parts to turn and move when 90 together. These ways are preferably curved, or in the form of a circle, with an extension out to the end of the side rails, as shown in Figs. 1, 3, and 4 of the drawings. To operate in these bearings or ways, two anti-friction 95 rollers, L, pivoted to the permanent portion of the bed, are provided at each side. The curved circular portion of the bearing moves on these rollers as the bed is opened or shut. By having the way extended out to the end of the side 100

rails the parts can be easily disconnected by simply lifting up the rear end of the bed-body when the bed is down, so as to bring the extension to the bearings in line with the rollers, 5 when the bed-body may be moved forward and the parts disconnected.

At the inner or head end of the bed-body I provide a head-board, C, which is hinged or flexibly connected to the bed-body at its lower 10 edge, as shown in Figs. 1 and 3. A cross-bar, D, is placed immediately above the upper end of the head-board C, so that it can move up and down in ways or grooves provided at each side of the permanent portion of the bed. The 15 lower edge of this bar D has studs or projections, and the upper edge of the head-board C has holes or sockets, enlarged at their bottoms, into which such studs or projections may extend and attach the two parts removably and 20 flexibly together, as shown in Fig. 5. Extending up from the bar D, and adapted to move up and down in the grooves or ways above mentioned, I preferably arrange two standards, E, which move up and down in the ways as the 25 bar D moves up and down. I attach ropes, chains, or cables to the upper ends of these standards and pass them around pulleys I, and attach their other ends to springs G. These 30 springs are preferably made of one or more bars or sheets of steel or other flexible metal arranged in a vertical position, their upper ends being securely attached to the permanent portion of the bed, and preferably bent against segments of circles H as their free ends are 35 pulled outward, though pins or other resisting means may be employed. In this way I make a connection between the springs and a movable portion of the bed, so that the springs may be bent, though variations in the precise means 40 of connection may be adopted.

It will be seen by referring to Fig. 3 and other figures of the drawings that as the bed-body is lowered the movable head-board C is raised. As it moves upward the bar D and 45 the standards E are carried upward also in the

ways provided for them. As they move upward, the cords or chains F are drawn around the pulleys I and the free ends of the springs G drawn outward. When the bed has been fully lowered, the springs will be drawn against 50 the segments H and will be in the condition of their highest tension. As the bed-body is raised the head-board, bar, and standards are lowered again and the springs allowed to straighten out and assume their normal position. These springs are made of sufficient tension to just about counterbalance the body of the bed before it is provided with the bedding and bedclothes.

To compensate for the additional weight 55 imparted to the bed-body by the bedclothes, weights may be put into the inner end of the folding portion of the bed, where a box or cavity, W, is provided to receive the same, as shown in Fig. 3. The weights thus added 60 should just about counterbalance the weight of the bedding and bedclothes, so that the bed-body can be lowered or raised with perfect ease, whether emptied or weighted.

What I claim as new, and desire to secure by 70 Letters Patent, is—

In a wardrobe-bedstead, the combination of a permanent or standing portion, a folding or bed portion opening from and closing to the standing portion, vertical springs secured 75 rigidly at one end to the back of the standing portion, curved resistants permanently secured to the back of the standing portion in the way of such springs when bent and against which they are brought in bending, and cords 80 or chains connecting the free ends of the springs with the movable or folding portion of the bed, whereby the springs are drawn against the resistants as the bed is lowered and their resiliency secured as the bed is raised, 85 substantially as described.

LEWIS G. KELLOGG.
